UNITED STATES PATENT OFFICE.

JAMES G. HUGHES, OF NEWARK, OHIO.

SHIPPING-TAG.

1,096,370.

Specification of Letters Patent. Patented May 12, 1914.

Application filed June 13, 1913. Serial No. 773,458.

To all whom it may concern:

Be it known that I, JAMES G. HUGHES, a citizen of the United States, residing at Newark, in the county of Licking and State 5 of Ohio, have invented a new and useful Improvement in Shipping-Tags, of which the following is a specification.

This invention relates to a shipping tag and while the device may be used wherever 10 an ordinary tag may be employed it is especially adapted for use with packages sent by parcel post, and the object of the invention is to strengthen the tag thereby avoiding danger of non-delivery of the package 15 by reason of damage to the tag attached thereto.

A further object of the invention is to facilitate the tying of packages designed to be sent by parcel post.

20 The invention consists of the novel features of construction hereinafter described, pointed out in the claims and shown in the accompanying drawings, in which:

Figure 1 is a face view of the tag. Fig. 25 2 is a view of the rear face of the tag. Fig. 3 is a section on the line 3—3 of Fig. 1. In these drawings 1 represents the tag, formed of suitable stiff paper or card board, and having upon its front face suitable 30 lines or spaces for the writing of names and addresses, and having also upon said face any desired and appropriate printed matter. The rear face of the tag is provided with a longitudinal metal strip the end portions 35 of which are bent over upon the end marginal portions of the front face of the tag. A transverse metal strip 3 also extends across the rear end of the tag and has its ends bent over upon the side marginal portions 40 of the front face of the tag. The strips 2 and 3 are secured to each other and also to the tag by a suitable rivet 4, which passes through the strips at their point of 45 intersection. Suitable securing tabs or buttons are arranged upon the front face of the tag.

tag and are secured by suitable eyelets or rivets which pass through the tag and also through the strips 2 and 3, respectively. These buttons are preferably so placed that they will slightly overlap the overturned 50 end portions of the metal strips, thereby preventing the fingers of anyone handling the package from coming into contact with the ends of the strips, and also preventing accidental forcing of said end portions out 55 of position. In tying the package the cord is of course passed around the buttons 5 in the usual manner. This affords a tag firmly braced both longitudinally and transversely, and not readily torn or destroyed, 60 and at the same time facilitates the tying and untying of the package to which the tag is applied.

What I claim is:—

1. The combination with a tag, of intersecting strips of reinforcing material carried by the rear face of the tag, said strips being secured to each other and to the tag at their point of intersection, the end portions of said strips being bent over upon 65 the front face of the tag, and cord securing devices carried by the front face of the tag, said cord securing devices being connected through the tag to said reinforcing means. 75

2. The combination with a tag, of intersecting metal strips extending across the rear face of the tag having their end portions bent over upon the front face of the tag, means securing said strips to each other 80 and to the tag at their point of intersection, and buttons arranged upon the front face of the tag and secured to said strips upon the back of the tag, a portion of said buttons overlapping the end portions of said 85 strips as and for the purpose set forth. 75

JAMES G. HUGHES.
